UNITED STATES PATENT OFFICE

FREDERICK L. NELSON, OF ALTA, IOWA

SHINGLE GAUGE

Application filed February 13, 1928. Serial No. 253,876.

The object of my invention is to provide a shingle gauge of simple, durable, and comparatively inexpensive construction.

A further object of my invention is to provide a shingle gauge by the use of which the danger of holes in the shingled roof is eliminated. Ordinarily the carpenter uses a straight edge to which two shingles have been nailed, and these shingles are fastened to the roof with shingle nails. Many times these nails are driven into the roof between the sheathing boards and when this is done, a hole in the roof results, which does not appear until the roof is completed, it then being too late to repair such leak and usually they are difficult to locate. My gauge is primarily designed to entirely eliminate this evil without the use of expensive equipment.

A further object is to provide a gauge consisting of a pair of members adapted to be clamped to an ordinary board such as found around any building during the course of construction with means on the members for extending under the lower edge of a row of shingles so that one edge of the board may be used for gauging the next row of shingles to be laid in position on the roof.

Still a further object is to provide the member **U** shaped in form so that it may fit over one of the edges of the board and to further provide a clamping bolt through the sides of the **U** shaped member for securely clamping these sides to the surfaces of the board.

Still a further object is to provide slots in the sides of the **U** shaped member for the clamping bolt to extend through so that the gauge board may be adjusted to different positions with respect to the **U** shaped members for gauging the shingles to overlap different distances as desired.

Still a further object is to provide several clamping bolts with different thicknesses of heads whereby shingles of various thicknesses may be gauged by my device.

With these and other objects in view my invention consists in the construction, arrangement and combination of the various parts of my device, whereby the objects contemplated are attained, as hereinafter more fully set forth, pointed out in my claims and illus-

trated in the accompanying drawings. Although the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawings in which:

Figure 1 is a plan view of my improved shingle gauge in use and illustrating two rows of shingles already laid and a third one being laid.

Figure 2 is a perspective view of the gauge itself as assembled for use.

Figure 3 is a sectional view on the line 3—3 of Figure 2 showing the device in use for engaging ordinary wood shingles, the shingles being shown in position on a roof.

Figure 4 is a similar view illustrating the device in use for asbestos or other types of shingles thinner than wood shingles.

Figure 5 is a perspective view of one of the clamping members, a pair of which are used in connection with the gauge board to comprise a complete shingle gauge;

Figure 6 is a detail sectional view on the line 6—6 of Figure 3.

On the accompanying drawings I have used the reference numeral 10 to indicate a row of shingles, a second row is indicated by the reference numeral 12, and a third row is indicated at 14. After the shingles 10 are laid, my gauging device is used for laying the second row 12 and then for laying the third row 14 and so on.

My gauge device comprises a pair of members **A** and a gauge board **B**. Each member **A** consists of a back member 16 and a pair of arms 18 and 20 whereby a substantially **U** shaped member is formed. The gauge board **B** is adapted to be inserted between the arms 18 and 20 as clearly illustrated in Figure 3 of the drawings. The board **B** may be any desired width and a 1 x 4 is the most suitable for the purpose. Boards of this character are always lying around a newly constructed house and by the arrangement of my device such material can be used with-

out the necessity of using a definite member for the gauge which would have to be kept all the time.

For securely holding the board B between the arms 18 and 20 by frictional engagement I provide a clamping bolt 22 having a wing nut 24 thereon. The bolt 22 is mounted through a slot 26 in the arm 18 and through a slot 28 in the arm 20. A recess 30 somewhat wider than the slot 28 is provided in the arm 20 for the purpose of receiving the square head 32 of the bolt 22 and thereby prevent its turning relative to the member A.

From the foregoing description it will be obvious that the gauge board B may be adjusted to any position within certain limits relative to the arms 18 and 20 so that the rows of shingles 10, 12, and 14 may be laid in overlapping position, the overlap being varied as desired.

The portion 16 of the member A extends beyond the arm 20 as indicated at 34 and has a finger extending in the same direction as the arms 18 and 20 and adapted to hook under the lower edge of the row of shingles as clearly illustrated in Figure 3. The bolt illustrated in Figures 3 and 6 is designed for wood shingles and another bolt illustrated in Figure 4 may be substituted for the bolt shown in Figure 3 when asbestos shingles or shingles thinner than the wood shingles are being laid. The bolt 22 illustrated in Figure 4 has an additional head 38 to fill up the intervening space between the bottom of the arm 20 and the top of the thinner shingle 40.

From the foregoing description it will be apparent that I have provided a pair of simple clamping members which may be clamped to the ends of a board so that the board may act as a gauge board. In moving from one job to another the carpenter needs only to take the members A with him, the gauge board B being any board suitable and in this manner my device is considerably simplified over the type of gauge in which the member B must be of specific construction.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. A device of the class described comprising a U shaped member, the arms thereof being longitudinally slotted, a clamping bolt extending through said slotted arms, and an extension on the connecting portion of the U-shaped member terminating in a finger bent to extend in the same direction as the arms of said U-shaped member.

2. In a device of the class described, a U-shaped member, the arms thereof being

longitudinally slotted, one of said arms having a counter-sunk recess surrounding the slot therein, a clamping bolt extending through said slotted arms and having a head located within said counter-sunk recess to prevent turning of the bolt, and an extension of the connecting portion of the U-shaped member, terminating in a finger bent to extend in the same direction as the arms of said U-shaped member.

3. In a device of the class described, a U-shaped member, the arms thereof being longitudinally slotted, one of said arms having a counter-sunk recess surrounding the slot therein, a clamping bolt extending through said slotted arms and having a head located within said counter-sunk recess to prevent turning of the bolt, an extension of the connecting portion of the U-shaped member, terminating in a finger bent to extend in the same direction as the arms of said U-shaped member and adjacent the arm having the recessed slot, said head having a portion thereon extending beyond the surface of the slotted arm having the counter-sunk recess therein and partially spanning the distance between such arm and said finger.

FREDERICK L. NELSON.
